(57) CLAIM

The ornamental design for a toilet brush, as shown and described.

DESCRIPTION

FIG. 1 is a perspective view of a toilet brush showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a bottom side perspective view thereof; and,

FIG. 9 is in FIG. 8.

The broken lines in FIGS. 9 and 10 demarcate enlarged areas and form no part of the claimed design; and the broken lines in FIG. 6 depict portions of the toilet brush that form no part of the claimed design.

1 Claim, 9 Drawing Sheets
